(54) **LOOM,SAIL CLOTH**

(76) Inventor: **James Richards**

James Nichols,
Letters Patent

The Schedule referred to in these Letters Patent and making part of the same, containing a description in the words of the said James Nichols himself of his improvement in manufacturing sail cloth.

The use of starch in the manufacture of sail cloth has always been highly prejudicial, and to do without it has hitherto been thought impossible: it causes the cloth to turn to mildew, and exclude it from our flag has been an object with our manufacturers more particularly in our country, as the Commissioners of the Navy have wished the cloth for the service of the United States to be without starch.

The different qualities of sail cloth are by us designated by the following Numbers, 1. 2. 3. 4. 5. 6. 7. 8. The four first numbers, double threads, the latter numbers are single numbered &c. have hitherto been manufactured without starching, but although it has been repeatedly tried, yet never succeeded in making the single thread cloth without the use of starch. I have accomplished this desirable object by continual experiment, attention, and expense. It will be necessary to proceed regularly through the different operations in the manufacture of flax, in order to afford an accurate and concise history explanation as, in every one more of cloth, there something to remark. The first operation is hacking and must be particularly attended to. The flax must be more hacked than is commonly done and the staple must be separated as nearly as possible. The quantity of loss therefore will be greater, and consequently the loss in the operation is greater to the manufacturer.

In the operation of spinning it is necessary that the fibers of the flax should be set on the frame previous to its being spun, without this the cloth cannot be made without starch. Attention must be paid to have the spun harder, or twisted for a longer time than has been . . . heretofore practiced as by twisting harder the fibers of the thread are not so easily raised impeding the road,

in the operation of carding and thus starch is rendered unnecessary. By thus spinning harder the operation of bleaching is rendered more difficult, more expensive, and more impossible. The thread must be left longer in the bleaching vat, handled with more care and twisted harder to discharge the dye from it.

In carding I use the same rods as formerly although at the first I had others made for the purpose. I now however make rods of the same size and plan as are used by others, and I have now for three or four months been manufacturing jail cloth of numbers 3 to 7. 8. without the use of starch, and as it has not been done before I solicit the benefit of a patent.

These experiments have been made in the Phoenix Mill at Patterson, N. Jersey (of which I am foreman) formerly owned by J. J. Farquhar, Esq., who invented no starch and whose instructions are such as to lead me to hope for further improvements in the manufacture of this article.

Augd. 11. 1852. James Richard
